Primary Examiner — Sandra S Snapp*Assistant Examiner* — Leisha N Price(74) *Attorney, Agent, or Firm* — Leason Ellis LLP**CLAIM**

We claim the ornamental design for a cutting tool for tree pruning, as shown and described.

DESCRIPTION

FIG. 1 is a top perspective view of a cutting tool for tree pruning showing our new design;

FIG. 2 is front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the cutting tool for tree pruning and form no part of the claimed design.

1 Claim, 4 Drawing Sheets(56)
